UNITED STATES PATENT OFFICE.

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY.

GRIPPER FOR LASTING MACHINES.

Original application filed July 23, 1923, Serial No. 653,291. Divided and this application filed April 7, 1928. Serial No. 268,328.

This invention relates to grippers for pulling uppers over lasts in machines for lasting boots and shoes, this application being a division of my copending application Serial No. 5 653,291, filed on July 23, 1923. The invention is illustrated as applied to a gripper especially adapted for use in a machine of that type in which the upper materials are gripped and pulled successively in different locations 10 along the edge of the shoe bottom, as disclosed, for example, in the above-mentioned copending application, but it is to be understood that the invention is not limited to grippers designed for machines of that particular 15 kind.

A well-known type of gripper extensively used heretofore in lasting machines comprises a pair of upper-gripping jaws which present between them an upper-receiving opening 20 extending in a laterally inclined downward direction, the pair of jaws consisting of a lower relatively fixed jaw and a cooperating upper jaw mounted on a vertically swinging link for bodily downward closing movement 25 toward the fixed jaw and also for swinging movement about its connection with the link in a laterally inclined downward direction toward the gripping face of the fixed jaw in closing. A gripper of that type is shown, 30 for example, in United States Letters Patent No. 1,005,284, granted on October 10, 1911, upon an application of S. W. Ladd and E. A. Stiggins. In such a gripper it has been recognized as desirable to delay or retard the 35 above-mentioned swinging movement of the movable jaw until after a substantial portion of its bodily downward movement has been completed, in order to afford better insurance that the movable jaw will be in a position to reach out over the margin of the upper materials when it first engages them and that it will therefore clamp them properly against the fixed jaw. This is especially desirable by 40 reason of the fact that at different portions of the edge of the shoe bottom there is likely to be a considerable variation in the angular relation of the margin of the upper materials to the plane of the insole and in the distance that they project beyond the edge of the insole. In the gripper shown in the above-mentioned Letters Patent there was accordingly 45 provided cam means arranged to act on a

shank portion of the movable jaw to delay the swinging movement of this jaw toward the fixed jaw in the first portion of its downward closing movement, and even to cause it to reach out still farther over the margin of the upper, and thereafter in the latter portion of the closing movement to impart to it a comparatively quick swinging movement toward the gripping face of the fixed jaw.

The present invention provides an improved construction affording still better insurance of the proper operation of a gripper in closing. In the illustrated application of the invention to a gripper of the same general type as that shown in the above-mentioned Letters Patent, control of the swinging movement of the movable jaw to delay and thereafter to accelerate such movement is effected by engaging its shank portion relatively near the axis of the jaw, as compared with the distance of its upper-gripping end from the axis, the construction shown comprising means for thus engaging a suitably formed cam face on the shank portion of the jaw at a progressively increasing distance from the axis during the bodily downward movement of the jaw. By thus engaging the jaw relatively close to its axis, especially in the first portion of its closing movement, when it is desired substantially to prevent it from swinging, control of its gripping end in the manner desired is greatly facilitated, 55 since a comparatively small variation in the contour of its cam face is all that is needed for properly controlling its more distant gripping end. As also more particularly herein illustrated, the movable jaw comprises 60 an angle lever having arms of unequal lengths with its gripping face at the outer extremity of its longer arm and the controlling cam face on the shorter arm; and both the longer arm of this lever and the cooperating fixed 65 gripper jaw are so extended that their upper-gripping end portions are offset a substantial distance laterally from the jaw-supporting and controlling portions of the gripper. The long laterally extending arm of the movable 70 jaw, in combination with the controlling means above described, affords a construction whereby swinging movement of the gripping end of the jaw is conveniently and effectively

controlled in such a manner as practically to insure the proper gripping of the upper materials.

The novel features of the invention will 5 now be more particularly described by reference to the accompanying drawings and thereafter pointed out in the claims.

In the drawings,

Fig. 1 is a view in side elevation of a gripper in which the invention is embodied, illustrating the first position of the gripper in relation to a shoe;

Fig. 2 is a view similar to Fig. 1, with parts in section, showing the gripper as it 15 appears at an intermediate stage in the closing movement of the movable jaw; and

Fig. 3 is a view similar to Fig. 2 showing the positions of the parts at the end of the closing movement.

Except as more particularly hereinafter described, the gripper herein shown is similar in its general organization to the gripper shown in the above-mentioned Letters Patent. It comprises a gripper jaw carrier 10 20 to the lower end of which is secured a jaw 12 which may be conveniently termed a fixed jaw, since it has no closing movement. Co-operating with the jaw 12 is an upper movable jaw 14 supported on the carrier 10 by means of a vertically swinging link 16, this jaw having a shank portion 18 extending upwardly above the link and connected by a short link 20 to the lower end of a closing rod 22 which is vertically movable in the carrier 25 10. It will thus be seen that by downward movement of the rod 22 there is imparted to the jaw 14 a bodily downward closing movement toward the jaw 12, accompanied by a downward swinging movement of the link 16. This link is initially inclined as shown in 30 Fig. 1, so that the jaw 14 in the first portion of its downward movement is carried somewhat to the left as the link swings to a horizontal position, after which, in its further 35 downward movement, the jaw has a component of movement toward the right in response to the action of the link, as will be evident by reference to Figs. 2 and 3.

Also in general similarity to the construction shown in the above-mentioned Letters Patent, there is fast on the carrier 10 a member 24 for engaging the shank 18 of the jaw 14 to control swinging movement of the jaw about the axis of its pivotal connection 26 55 with the link 16, and the shank 18 has therein a spring plunger 28 which acts on a lug 30 fast on the link 20 with a tendency to swing the lower end of the link toward the right and thereby to hold the shank 18 of the jaw continuously in contact with the member 24.

It will be understood that in operation the gripper as a whole, including the carrier 10 and the closing rod 22, is moved downwardly and toward the left from the position in 60 which it is shown in Fig. 1 preparatory to

gripping the margin *a* of the upper materials of a shoe held in the hands of an operator in a position determined by a sole rest 32. After the gripper has thus been moved into position to grip the upper, closing movement is imparted to the jaw 14 through downward movement of the rod 22, whereupon the gripper is moved upwardly and toward the right to pull the upper over the last. The means for imparting operative movements to the 70 jaw carrier 10 and to the closing rod 22 are not shown herein, since the construction of such means is well known and is, moreover, fully disclosed in the copending application of which this application is a division. 75

In the construction provided for purposes of this invention the gripper jaws 12 and 14 comprise elongated arms projecting laterally of the jaw carrier 10 and provided with upper-gripping faces at their outer extremities in 80 locations offset a substantial distance from the axis of the closing rod 22. The movable gripper jaw 14 is, moreover, formed as an angle lever with its gripping arm considerably longer than that arm which constitutes 85 the upwardly extending shank portion 18 of the jaw, the pivotal connection 26 between the jaw and the link 16 being located at the apex of the angle between the two arms. To control as desired the swinging of the jaw 14 about its connection with the link 16, the shank portion 18 of the jaw has a cam face suitably formed for continuous engagement 90 during the downward movement of the jaw with a nose or abutment 34 on the lower end of the controlling member 24. As illustrated, the cam face on the shank 18 comprises a projection 36 in a location near the axis 26, a hollow 38 immediately above this projection, and another projection 40 above the hollow 38. Initially the parts are so positioned that the projection 36 of the shank 18 is in engagement with the abutment 34, as shown in 95 Fig. 1, to prevent contact of the outer end of the jaw 14 with adjacent parts of the machine in which the gripper is utilized. As bodily downward movement is imparted to the jaw 14 by the closing rod 22, after the gripper has been moved into upper-gripping position, the hollow or depression 38 of the shank 18 arrives in position to engage the abutment 34 in the first part of such downward movement, thus delaying the swinging movement of the jaw 14 about its connection to the link 16 in 100 a direction toward the fixed jaw 12, as illustrated in Fig. 2. It will further be noted that this action coincides substantially with the movement of the jaw 14 toward the left by the swinging of the link 16 to horizontal position, as hereinbefore described, 105 the result being that the jaw 14 reaches out farther over the margin of the upper without swinging inwardly toward the gripping face of the jaw 12. In the further downward movement of the closing rod 22 the projection 110 115 120 125 130

40 on the shank 18 is engaged by the abutment 34, whereby a quick swinging movement about the axis 26 is imparted to the jaw 14 to carry its gripping face laterally toward the 5 gripping face of the jaw 12 in the latter portion of the closing movement, this action coinciding with the lateral bodily movement of the jaw resulting from the swinging of the link 16 below horizontal position. It will thus be 10 seen that in the closing of the gripper the gripping arm of the jaw 14 reaches out to insure that it will be properly positioned in relation to the margin of the upper before any substantial movement of the upper-gripping 15 face of the jaw toward the fixed jaw 12 takes place, and then swings sharply inward toward the fixed jaw with a large component of lateral movement as distinguished from downward vertical movement to grip the margin of 20 the upper materials evenly and firmly without danger of pushing them downwardly before they are gripped.

It will be evident that an important factor in obtaining the desired results by the 25 use of the construction above described is the means for controlling the swinging movement of the movable gripper jaw by engaging it comparatively close to the axis about which it swings. Since the shank portion 30 or arm 18 of the jaw is substantially shorter than the upper-gripping arm, and furthermore since the abutment 34 engages the arm 18 between its opposite ends, the effective length of the lever arm through which control of the swinging movement of the jaw 35 is effected is at all times substantially less than the length of the gripping arm, and especially so in the first portion of the downward closing movement of the jaw when its 40 swinging movement is retarded by the cooperative action of the abutment 34 and the hollow 38 in the arm 18. Accordingly, control of the upper-gripping end of the jaw in such manner as to produce the most satisfactory 45 results can be effected, as shown, by the use of a cam face on the arm 18 not involving any very pronounced variation in contour and well within the limits of practical design.

Having described the invention, what I 50 claim as new and desire to secure by Letters Patent of the United States is:—

1. A gripper for a lasting machine having, in combination, a jaw carrier having a relatively fixed gripping jaw thereon, a cooperating jaw so mounted as to have a combined bodily movement and swinging movement toward the fixed jaw in the closing of the gripper, the axis of swinging movement of the movable jaw being so located as to divide 55 the jaw into a gripping arm at one side of the axis and a shank portion at the other side of the axis, and controlling means on the carrier arranged to engage the shank portion of the movable jaw first in a location compara-

tively near said axis and then in locations successively farther from said axis in the closing movement to control the swinging of the jaw in closing, said controlling means and the shank portion of the movable jaw being 70 so formed as to delay the swinging of said jaw toward the fixed jaw in the first portion of its closing movement and to impart thereto a relatively quick swinging movement toward the fixed jaw in the latter portion 75 of the closing movement.

2. A gripper for a lasting machine having, in combination, a jaw carrier having a relatively fixed gripping jaw thereon, a cooperating jaw so mounted as to have a combined 80 bodily movement and swinging movement toward the fixed jaw in the closing of the gripper, the axis of swinging movement of the movable jaw being so located as to divide the jaw into a gripping arm at one side 85 of the axis and a shank portion at the other side of the axis, and a controlling abutment on the carrier arranged to engage the shank portion of the movable jaw first in a location 90 comparatively near said axis and then in locations successively farther from said axis in the closing movement to control the swinging of the jaw in closing, said shank portion of the movable jaw having a cam face thereon engaged by said abutment and including 95 a hollow portion for delaying the swinging of said jaw toward the fixed jaw in the first portion of its closing movement and a projection for imparting thereto a relatively quick swinging movement toward the fixed 100 jaw in the latter portion of the closing movement.

3. A gripper for a lasting machine having, in combination, a jaw carrier having a relatively fixed gripping jaw thereon, a cooperating jaw so mounted as to have a combined 105 bodily movement and swinging movement toward the fixed jaw in the closing of the gripper, the axis of swinging movement of the movable jaw being so located as to divide the jaw into a gripping arm at one side 110 of the axis and a shank portion at the other side of the axis, and a member on the carrier arranged to engage the shank portion of the movable jaw in locations at different 115 distances from said axis successively in the closing movement to control the swinging of the jaw in closing, said shank portion having therein a depression to receive said member and thereby delay the swinging of the movable jaw toward the fixed jaw in the first portion of its closing movement.

4. A gripper for a lasting machine having, in combination, a jaw carrier having a relatively fixed gripping jaw thereon, a cooperating jaw so mounted as to have a combined 120 bodily movement and swinging movement toward the fixed jaw in the closing of the gripper, the axis of swinging movement of the movable jaw being so located as to divide 125 the jaw into a gripping arm at one side of the axis and a shank portion at the other side of the axis, and controlling means on the carrier arranged to engage the shank portion of the movable jaw first in a location compara-

jaw into lever arms of unequal lengths with the gripping face at the end of the longer arm, and controlling means on the carrier arranged to engage the shorter arm of the movable jaw in locations at different distances from said axis successively in the closing movement to control the swinging of the jaw in closing, said controlling means and the portion of the movable jaw engaged thereby being so formed as to delay the swinging of said jaw toward the fixed jaw in the first portion of its closing movement and to impart thereto a relatively quick swinging movement toward the fixed jaw in the latter portion of the closing movement.

5. A gripper for a lasting machine having, in combination, a jaw carrier, a relatively fixed gripping jaw projecting laterally of said carrier, a cooperating jaw also projecting laterally of said carrier and formed as an angle lever with arms of unequal lengths and with its gripping face at the end of the longer arm, said last-named jaw being so mounted as to have a combined bodily movement and swinging movement toward the fixed jaw in the closing of the gripper, the axis of said swinging movement being located substantially at the junction of said lever arms, and controlling means on the carrier arranged to engage the shorter arm of the movable jaw first in a location comparatively near said axis and then in locations successively farther from said axis in the closing movement to control the swinging of the jaw in closing, said controlling means and the portion of the movable jaw engaged thereby being so formed as to delay the swinging of said jaw toward the fixed jaw in the first portion of its closing movement and to impart thereto a relatively quick swinging movement toward the fixed jaw in the latter portion of the closing movement.

6. A gripper for a lasting machine having, in combination, a jaw carrier having a relatively fixed gripping jaw thereon, a cooperating movable jaw comprising a gripping arm and a shank portion, a link pivoted on said jaw carrier for swinging movement toward and from the fixed jaw and pivotally supporting the movable jaw at a point substantially at the junction of its gripping arm and its shank portion, means for imparting to the movable jaw a bodily closing movement toward the fixed jaw while swinging said supporting link, and an abutment on said jaw carrier arranged to engage the shank portion of the movable jaw in locations successively farther from the connection of the latter with the link during the closing movement to control swinging movement of the jaw about said connection, the shank portion of said jaw having a hollow therein to cooperate with said abutment to delay swinging of the jaw toward the fixed jaw in the first portion of the closing movement.

7. A gripper for a lasting machine having, in combination, a jaw carrier having a relatively fixed gripping jaw thereon, a cooperating movable jaw comprising a gripping arm and a shank portion, a link pivoted on said jaw carrier for swinging movement toward and from the fixed jaw and pivotally supporting the movable jaw at a point substantially at the junction of its gripping arm and its shank portion, means for imparting to the movable jaw a bodily closing movement toward the fixed jaw while swinging said supporting link, and an abutment on said jaw carrier arranged to engage the shank portion of the movable jaw in locations at different distances from its connection with the link successively in the closing movement to control swinging movement of the jaw about said connection, the shank portion of said jaw having a cam face engaged by said abutment and so formed as to delay swinging of the jaw toward the fixed jaw in the first portion of the closing movement and to impart thereto a relatively quick swinging movement toward the fixed jaw in the latter portion of the closing movement.

8. A gripper for a lasting machine having, in combination, a jaw carrier having a relatively fixed lower gripping jaw thereon, a cooperating upper jaw, a link supporting said upper jaw on the jaw carrier for bodily closing movement toward the lower jaw and also for swinging movement toward the lower jaw about its connection with the link, said upper jaw having a shank portion extending upwardly above the link, and a member on the jaw carrier above the link having at its lower end a projection arranged for continuous engagement with said shank portion of the upper jaw during the closing movement of the latter to control the swinging of said jaw about its connection with the link, said shank portion having a cam face engaged by said projection and so formed as to delay swinging of the upper jaw toward the lower jaw in the first portion of the closing movement and to impart thereto a relatively quick swinging movement toward the lower jaw in the latter portion of the closing movement.

9. A gripper for a lasting machine having, in combination, a jaw carrier, a closing rod movable lengthwise in said carrier, a pair of cooperating gripping jaws projecting laterally of said carrier with gripping faces at their outer extremities in locations offset a substantial distance from the axis of the closing rod, one of said jaws being fixed on the carrier and the other mounted for bodily closing movement toward the fixed jaw and also for swinging movement toward said jaw in closing, means connecting the movable jaw to the closing rod, and means on the carrier for engaging a portion of the movable jaw to control its swinging movement, said means being arranged to engage

the jaw initially in a location at a shorter distance from the axis of its swinging movement than that between said axis and the gripping face of the jaw and constructed to 5 cooperate with the portion of the jaw engaged thereby to delay the swinging of the jaw toward the fixed jaw in the first portion of the closing movement and to impart thereto a relatively quick swinging movement 10 toward the fixed jaw in the latter portion of the closing movement.

10. A gripper for a lasting machine having, in combination, a jaw carrier, a closing rod movable lengthwise in said carrier, a pair of 15 cooperating gripping jaws projecting laterally of said carrier with gripping faces at their outer extremities in locations offset a substantial distance from the axis of the closing rod, one of said jaws being fixed on 20 the carrier, a link supporting the other jaw on the carrier for bodily closing movement toward the fixed jaw and also for swinging movement toward the fixed jaw about an axis at its connection with the link, said movable 25 jaw having a shank portion at one side of said axis shorter than the portion of the jaw at the other side of said axis, means connecting said shank portion to the closing rod, and an abutment on the jaw carrier arranged 30 to engage the shank portion of the movable jaw in locations successively farther from said axis in the closing movement to control the swinging of the jaw, the shank portion of said movable jaw having a cam face engaged by said abutment and so formed as 35 to delay swinging of the jaw toward the fixed jaw in the first portion of the closing movement and to impart thereto a relatively quick swinging movement toward the fixed jaw in 40 the latter portion of the closing movement.

11. A gripper for a lasting machine having, in combination, a jaw carrier, a closing rod movable lengthwise in said carrier, a pair of 45 cooperating gripping jaws projecting laterally of said carrier with gripping faces at their outer extremities in locations offset a substantial distance from the axis of the closing rod, one of said jaws being fixed on

the carrier, the other jaw comprising an angle lever having arms of unequal lengths with 50 the gripping face at the end of the longer arm, a link connected to said last-named jaw in a location substantially at the apex of its angle and supporting said jaw on the carrier for bodily closing movement toward 55 the fixed jaw and also for swinging movement toward said jaw about its connection with the link, means connecting the shorter arm of the movable jaw to the closing rod, and means on the carrier arranged to act on 60 said shorter arm to delay swinging of the movable jaw toward the fixed jaw in the first portion of the closing movement and to accelerate such swinging movement in the latter portion of the closing movement. 65

12. A gripper for a lasting machine having, in combination, a jaw carrier, a closing rod movable lengthwise in said carrier, a pair of 70 cooperating gripping jaws projecting laterally from said carrier with gripping faces at their outer extremities in locations offset a substantial distance from the axis of the closing rod, one of said jaws being fixed on 75 the carrier, the other jaw comprising an angle lever having arms of unequal lengths with the gripping face at the end of the longer arm, a link connected to said last-named jaw in a location substantially at the apex of its angle and supporting said jaw on the carrier for bodily closing movement toward the fixed 80 jaw and also for swinging movement toward said jaw about its connection with the link, means connecting the shorter arm of the movable jaw to the closing rod, and a device on the carrier arranged to engage said shorter arm in locations successively farther from its connection with the link in the closing movement to control the swinging movement 85 of the movable jaw, said arm having a cam face engaging said controlling device and so formed as first to delay and then to accelerate the swinging of the movable jaw toward the fixed jaw. 90

In testimony whereof I have signed my name to this specification.

GEORGE GODDU.
